MAILING DEVICE

Abraham Deutschmeister and Herman
Deutschmeister, New York, N. Y.

Application October 3, 1942, Serial No. 460,644

4 Claims. (Cl. 229—73)

Our present invention relates to mailing devices and more particularly to devices of the general character indicated adapted to permit two-way mailing.

It is the main object of the present invention to provide a mailing device so designed that a message may be included therein on the outgoing trip, for example, a request for a payment on an installment account, and so designed as to permit the device to be sealed and returned to the original sender with an enclosure, such as a check in response to such request.

Our present invention aims to provide a device for the purposes indicated which is simple in construction, easy and economical to fabricate and assemble and which is admirably adapted to perform the intended functions.

In the accompanying specification we shall describe and in the annexed drawing show an illustrative embodiment of the mailing device of the present invention. It is however, to be clearly understood that the present invention is not to be limited to the exact details of construction herein shown and described for purposes of illustration only, inasmuch as changes therein may be made without invention and within the scope of the claims hereto appended.

In the accompanying drawing,

Figure 1 is a plan view of the aforesaid illustrative embodiment of the present invention, shown in condition to be sent out on the original trip.

Figure 2 is a similar view of the same, shown in condition permitting the addressee to read the message borne thereby.

Figure 3 is a similar view of the same, shown in a condition permitting the re-mailing of the device back to the original addressor; and

Figure 4 is a transverse sectional view taken along line 4—4 of Figure 3.

Referring now more in detail to the aforesaid illustrative embodiment of the present invention and with particular reference to the drawing illustrating the same, the numeral 10 generally designates an envelope or carrier portion of the mailing device of the present invention, which carrier portion includes a section 11, comprising a rear wall, two side sections 12 and 13 integrally formed with the section 11 and adapted to be folded thereover, as best seen in Figure 2, and a section 14, likewise integrally formed with the section 11 and adapted to be folded over the two side sections, the sections 12, 13 and 14 comprising a front wall, and the arrangement being

such that the sections 11, 12, 13, and 14 constitute an envelope closed on three sides.

Integrally formed with the section 11 and extending therefrom along the edge opposite that from which the section 14 extends, is a flap 15, the flap being provided, along its upper edge, as at 16, with sealing gum, the flap being adapted to bear, on the inner surface thereof, a message 17 and instructions 18 as to how the device is to be used for the return trip.

The section 14 is provided with a flap 19, defined on three sides, by lines of perforations 20, and on the fourth side, by a score line 21, this flap being adapted to bear, on its outer surface, the name and address 22 of the original addressee.

The section 12, is adapted to bear the name and address 23 of the original addressor and the section 13 is adapted to bear, in the upper right hand corner thereof, the postage stamp 24, or other postage indicia.

This completes the description of the structure of the aforesaid illustrative embodiment of the present invention and the manner of using the same may be briefly summarized as follows:

- 25 For the outgoing trip, the flap 15 is tucked within the carrier 10 intermediate the rear and front walls thereof, the section 12 bearing the name and address of the addressor, the flap 19 bearing the name and address of the addressee, and the section 13 bearing the postage stamp. When the carrier is received by the addressee, the flap 15 is removed from between the walls thereof and the message 17 read. By following the instructions 18, likewise borne by the flap 15, the carrier can be used for return mailing. These instructions are carried out by first pushing in the flap 19, the same being separable from the front wall of the carrier along the lines of perforations 20. This flap is folded back against the inner surface of the front wall of the carrier along the score line 21. This operation leaves an opening 25 in the front wall of the carrier and this reveals the name and address 26 of the original addressor who has now become the addressee, this name and address being printed upon the inner surface of the rear wall of the carrier. The flap 15 which was originally tucked within the carrier can now be sealed over the front wall of the carrier and the outer surface thereof may bear the name and address 27 of the addressor who was the original addressee. In the opposite corner of the flap 15, there may be placed a postage stamp 28 for the return trip. It will be noted that the flap 15, in its position for the return trip, in addition to sealing the

envelope, which may now contain a check 29 or other enclosure carried intermediate the inner surface of the front wall and the folded back flap 19, serves to conceal the name and address 23 of the original addressor and the cancelled post mark for the outgoing trip.

If desired, the flap 19, may be provided with a gummed edge so that when it is folded back against the front wall of the carrier, it can form a sealed pocket to enclose coins, etc.

This completes the description of the mode of use of the present invention and it will be noted from all of the foregoing that there is provided a two-way mailing device which is simple in construction, easy and economical to fabricate and assemble and which is admirably adapted to perform the intended functions.

What we claim as our invention is:

1. A two-way mailing device comprising a carrier portion including front and rear walls, said front wall being provided with a score line and lines of perforations defining a flap adapted to bear a mailing address, said flap being separable from said front wall along said perforations, and being foldable along said score line back against the inner surface of said front wall to present an opening, in said front wall, revealing a return address borne by the inner surface of said rear wall.
2. A two-way mailing device comprising a carrier portion including front and rear walls, and a message bearing flap adapted to be tucked intermediate said walls on the outgoing trip, said front wall being provided with lines of perforations defining a second flap adapted to bear a mailing address, said second flap being separable from front wall along said perforations to present

an opening, in said front wall, revealing a return address borne by the inner surface of said rear wall, and said first flap being removable from said carrier portion to seal the latter and simultaneously conceal the outgoing cancelled post mark for the return trip.

3. A two-way mailing device comprising a carrier portion including front and rear walls, and a message bearing flap adapted to be tucked intermediate said walls on the outgoing trip, said front wall being provided with a score line and lines of perforations defining a second flap adapted to bear a mailing address, said second flap being separable from said front wall along said perforations and being foldable along said score line back against the inner surface of said front wall to present an opening, in said front wall, revealing a return address borne by the inner surface of said rear wall, and said first flap being removable from said carrier portion to seal the latter and simultaneously conceal the outgoing cancelled post mark for the return trip.

4. A two-way mailing device comprising a carrier portion including front and rear walls, said front wall being provided with a score line and lines of perforations defining a flap adapted to bear a mailing address, said flap being separable from said front wall along said perforations, and being foldable along said score line back against the inner surface of said front wall to present an opening, in said front wall, revealing a return address borne by the inner surface of said rear wall, and to cooperate with said front wall to form a pocket.
